UNITED STATES PATENT OFFICE.

SAMPSON JOHN MISENER, OF WOODSIDE, DARTMOUTH, NOVA SCOTIA, CANADA.

TRAVELING-GRAVE FURNACE.

1,073,359.

Specification of Letters Patent. Patented Sept. 16, 1913.

Application filed March 29, 1912. Serial No. 687,244.

To all whom it may concern:

Be it known that I, SAMPSON JOHN MISENER, of Woodsid, Dartmouth, in the Province of Nova Scotia, Dominion of Canada, have invented certain new and useful Improvements in Traveling-Grate Furnaces; and I do hereby declare that the following is a full, clear, and exact description of the same.

10 This invention relates more particularly to the bridge piece or arch over which the ashes are discharged to the ash pit in automatic stoking furnaces of this type and it has for an object to provide an improved 15 and simplified construction of such bridge piece by which entrance of air to the fire chamber at the point where such bridge piece is located will be prevented.

For further comprehension of the invention, and of the objects and advantages thereof, reference will be had to the following description and appended claims, and to the accompanying drawings forming part of this specification, in which similar reference 25 characters indicate the same parts and wherein—

Figure 1 is a vertical sectional view of the lower part of a traveling grate furnace having my invention applied thereto, and Fig. 2 30 is a horizontal section taken on the line 2—2 Fig. 1.

Referring now to the drawings 1 indicates the automatic stoking traveling grate of usual chain construction of a furnace and 35 looped at its opposite ends over a pair of sprocket wheels, 2 and 3 respectively, located at the front and rear of the furnace, while the ash pit into which the ashes are discharged from the grate is indicated at 4. I 40 have indicated in dotted lines at 5 and 6 the usual hopper and feed control doors of a furnace of this type, such parts however having nothing to do with the present invention.

45 Referring now to the features of construction constituting my invention I provide at the rear end of the grate adjacent the point where it loops around the sprocket wheel 3 a pipe 10 extending transversely across the 50 fire chamber 11 of the furnace with its opposite ends embedded in the side walls 12 of the furnace as shown most clearly in Fig. 2. The intermediate portion 10' of this pipe, or that extending over the grate, is of 55 triangular or wedge shape in cross section with the apex of the wedge turned toward

the front of the furnace and located quite close to the top of the grate. This pipe forms the upper front end of the bridge piece or arch which curves downwardly and rearwardly over the rear sprocket support for the grate and separates the ash pit 4, having the usual dumping door 17, from the grate chamber. This arch is preferably composed of an inner or bottom plate 18 60 steel bolted or otherwise suitably secured at its top edge to the underside of the pipe portion 10' and at its lower edge to a cross bar 19 embedded at opposite ends in the walls 12. Upon this plate 18 is placed a layer of 65 asbestos millboard or the like upon which rests a layer 19' of fire brick or suitable refractory material. This layer 19' of fire brick may either be composed of a plurality of bricks of ordinary size or of a smaller 70 number of larger bricks molded to the required shape to form the arch. To insure against the bricks in the upper part of the arch working loose I may provide a series of pins 19^a fixed to the pipe 10 and projecting into 75 recesses in the said bricks.

Water or other suitable cooling medium may be supplied to the pipe 10 by means of a second pipe 20 of reduced diameter inserted in the pipe 10 near one end thereof, 80 which end projects through the side wall 12 as shown, and extending through the pipe 10 to a point near its opposite end, the inner 85 end of the pipe 20 being open to cause the water to be discharged into the pipe 10, the 90 water escaping through an outlet pipe 21 leading into the pipe 10 adjacent a cap 22 upon the said end of the pipe 10.

To prevent any tendency of the fuel to form in clinkers a steam pipe 25 may extend 95 across the furnace underneath the upper reach of the chain (which constitutes the grate) and adjacent the sprocket 3 this pipe having upwardly facing perforations 26 through which the steam is discharged.

What I claim is as follows:

1. In a traveling grate furnace, in combination, a traveling grate, a device located adjacent the rear end of the grate and adapted to have the ashes discharged thereover and comprising a metallic member wedge shaped in cross section with the apex of the wedge toward the front of the grate and in close proximity to the latter, means for causing water to circulate through said metallic member, an arch curving downwardly and rearwardly from said metallic 105 110

member and having an inner metallic plate and an outer covering of firebrick.

2. In a traveling grate furnace, in combination, a traveling grate, a device located adjacent the rear end of the grate and adapted to have the ashes discharged there-over and comprising a pipe bent to wedge shape in cross section with the apex of the wedge toward the front of the grate, means for causing water to circulate through said pipe, an arch curving backwardly and downwardly from the said pipe and consisting of an inner metallic plate secured at its forward end to the said pipe, a heat insulating lining placed over such plate, and a covering of firebrick placed over the said lining.

3. In a traveling grate furnace, in combination, a traveling grate, a device located adjacent the rear end of the grate and adapted to have the ashes discharged there-over and comprising a pipe having its ends of circular cross section and supported in the side walls of the furnace, the portion of the pipe between such side walls being bent

to wedge shape in cross section with the apex of the wedge toward the front of the grate, a water cooled pipe extending through such wedge shaped pipe and terminating short of one end thereof, an arch curving backwardly and downwardly from the said pipe and consisting of an inner metallic plate having its forward end projecting under and secured to the wedge shaped portion of the pipe, a heat insulating lining placed over such plate, a covering of firebrick placed over such lining, and a means comprising a series of pins projecting rigidly from the said pipe and embedded in the said fire brick for securing the latter in position.

In testimony whereof, I have signed my name to this specification, in the presence of two subscribing witnesses.

SAMPSON JOHN MISENER.
